UNITED STATES PATENT OFFICE.

GIOVANNI STRIZZI, OF NEW CASTLE, PENNSYLVANIA.

CRUSHING AND SEPARATING MACHINE.

Application filed February 9, 1923. Serial No. 618,114.

To all whom it may concern:

Be it known that I, GIOVANNI STRIZZI, a citizen of Italy, residing at 946 South Mill St., New Castle, in the county of Lawrence 5 and State of Pennsylvania, have invented certain new and useful Improvements in Crushing and Separating Machines, of which the following is a specification, reference being had therein to the accompanying 10 drawings.

This invention relates to a crushing and separating machine and it has for its object to provide an improved device of this character adapted to crush tomatoes and to rapidly 15 and expeditiously separate the skins and seeds from the juice and "meat" of the tomatoes and to discharge the latter from the machine.

It is a further object of the invention to 20 provide a machine of the character indicated which will be of very simple and economical construction, which will not be likely to get out of order and which may be readily and thoroughly cleaned with a minimum of 25 labor after being used.

Further objects and advantages of the invention will be set forth in the detailed description which follows:

In the accompanying drawing:

30 Fig. 1 is a longitudinal sectional view through the machine; and

Fig. 2 is a plan view thereof with the upper half of the machine thrown back upon its hinges.

35 Like numerals designate corresponding parts in both of the figures of the drawing.

The machine of the present invention comprises a box-like lower portion 5 having an inclined bottom 6 which is preferably cov-

ered with some non-corrodible sheet metal 7, such as tin, zinc, aluminum, copper or the like. A rectangular frame 8 corresponding in outline to the box 5 is hinged upon said box 5 at 9. The upper half 10 of a cylinder 40 is mounted within and moves with the rectangular frame 8 and carries a hopper extension 11 having a closure plug or cap 12. The hopper 11 and the upper half of the cylinder may be thrown back bodily with the

50 frame 8, if desired, but, during the operation of the machine these parts are locked in the position illustrated in Fig. 1 by hooks 13 and eyes 14. The lower half of the cylinder, indicated at 15, is carried by the box

55 5, and is perforated substantially throughout its area. It will be observed that any

matter expressed through the openings in the cylinder 15 will drop upon the inclined bottom 7 and as it accumulates thereon will be discharged out of the open front 16 of the 60 box 5. A row of hook like elements 17 carried by the front wall of the box 5 projects into the path of movement of a dasher 18 which is of flat plate like formation but has its corner cut away as indicated at 19 and 20 65 and is notched as indicated at 21 and 22 to form openings through which the hooks 17 pass. The dasher 18 is mounted upon a shaft 23. Lower bearings 24 carried by the box 5 receive the shaft and upper bearings 70 26 carried by the frame 8 rest upon the shaft and hold it in position in the lower bearings 24 when the parts are in the position illustrated in Fig. 1. With the parts in this position tomatoes may be introduced into the cylinder formed by the halves 10 and 75 15, through the hopper 11 and they may be in partially crushed condition when they are introduced into this hopper. The edges of the dasher are rounded off, as indicated at 80 27. The dasher is rotated in the direction of the arrow and the rounded portions of the dasher catch the partially crushed tomatoes and wipe or rub them over the perforated lower half of the cylinder 15 thus releasing 85 the juice and forcing some of the meat through the perforations of the cylinder. This operation is continued until all of the "meat" of the tomato and all of the juice has been expressed through the opening. As the 90 material being crushed is brought around time after time, more and more of the meat and juice are expressed until finally nothing is left in the cylinder except the skins and seeds. 95

It is not to be understood that it is essential that the tomatoes be partly crushed when placed in the hopper 11. This is not the case, for whole tomatoes may be placed in the machine and as the dasher rotates these 100 whole tomatoes will be forced against the hooks 17 and initially ruptured and as rotation of the dasher continues the reduction of the pieces of tomatoes will be continued and they will become smaller and smaller in size 105 as they are alternately rubbed over the perforate lower portion of the cylinder and carried past the hooks 17.

It is to be understood that the invention is not limited to the precise construction set 110 forth but that it includes within its purview whatever changes fairly come within

either the terms or the spirit of the appended claims.

Having described my invention what I claim is:

- 5 1. A machine of the character described comprising a cylinder having a perforated lower portion, a dasher of plate-like formation therein, said dasher having its corners cut away and hooks carried by the cylinder disposed in the path of the cut out portions 10 of the dasher as and for the purposes set forth.
2. A machine of the character described comprising a two-part cylinder the upper 15 part of which is removable from the lower part and the lower part of which cylinder

is perforated, a shaft mounted between the upper and lower portions of the cylinder and having an operating handle thereon, a dasher of plate like formation carried by the shaft and disposed within the cylinder and having edges adapted to exercise a rubbing action upon tomatoes in forcing them over the perforated portions of the cylinder, said dasher having its corners 25 cut away and hooks fixed within the cylinder and in line with the cut-out portions of the dasher.

In testimony whereof I hereunto affix my signature.

GIOVANNI STRIZZI.
